Primary Examiner—Ralf Seifert
Attorney, Agent, or Firm—Schweitzer Cornman Gross & Bondell LLP**[57]****CLAIM**

The ornamental design for a jewelry chain, as shown and described.

DESCRIPTION

FIG. 1 is a top plan view of a sectional length of a jewelry chain according to the invention shown in a non-fastened, non-use position, the bottom plan view being a mirror image;

FIG. 2 is a first side edge elevation view thereof, the opposite side view being a mirror image;

FIG. 3 is a first end elevation view thereof, the opposite view being a mirror image; and,

FIG. 4 is a top plan view of a sectional length of the jewelry chain shown in a fastened, use configuration.
